UNITED STATES PATENT OFFICE.

HUGH M. KENNEDY, OF MONTREAL, QUEBEC, CANADA, ASSIGNOR TO THE ROBERT MITCHELL COMPANY LIMITED, OF MONTREAL, CANADA.

REVOLVING DOOR.

Application filed December 9, 1926. Serial No. 153,623.

This invention relates to new and useful improvements in revolving doors and particularly to the sealing means therefor, and the object of the invention is to provide 5 a simple and efficient means for sealing the door frames at their inner edge so that no draughts will pass between said edges and the door supporting means.

Another object is to provide a plurality 10 of weather strips which will be very easily attached to the door and which will not interfere with the free working of same.

In my invention I provide a plurality of 15 rubber, or like weather strips, which are detachably secured by means of clamps to the supporting means of a revolving door. The weather strips or sealing means may be made of tubular form, or they may be made of thin flexible rubber strips bent to form 20 air pockets which press the outer face of the strip against the inner edge of the doors when they are in their normal or working condition. The strips are positioned between the clamps and held in position so 25 that they revolve with the door. The outer edges of the door frames engage with the door enclosure through the medium of flexible rubber strips. The top and bottom of each of the door frames are also provided 30 with flexible weather stripping.

In the drawing which illustrates my invention in one of its forms;

Figure 1 is a side elevation of one type of 35 door upon which my improved weather strip or centre sealing means may be secured.

Figure 2 is a sectional plan of the revolving 40 door taken on the line 2—2 Figure 1.

Figure 3 is an enlarged sectional plan of 45 the centre of the door showing the method employed to hold the sealing or weather strip in position.

Referring more particularly to the drawings, 11 designates the door enclosure, the upper portion 12 of which is substantially 45 horizontally disposed and apertured to receive the uppermost end of a shaft or spindle 13. This end of the spindle is provided with a nut 27 which rests on a ball bearing 28, mounted on the shaft and engaging with a cross-head 29, which is provided with travelling wheels 30 which run in channels 31 secured to part of the upper portion 12 of the enclosure. The lower end 50 32 of the spindle is pivotally supported on a centre floor socket 33. The sides 14 of

the enclosure are each made in the form of an arc, the radius of which is swung from the centre of the spindle 13. The sides each extend through an angle of slightly more than ninety degrees so that at all times 60 the door, when in its operative position, will be sealed in the manner hereinafter described. The revolving portion of the device consists of four door frames 15, each disposed at an angle of ninety degrees to one another and radiating from the centre of the spindle 13. The door being mounted on a trolley, namely the aforementioned crosshead and its supporting wheels, allows the movable sections of the door to be moved to one side of the enclosure. The sections may be pivotally secured to discs 16, secured to the centre post 17 rotatably mounted on the spindle 13. Chains 18 or such like 65 tying members may be connected between the adjacent sides of the door to hold them in their normal working positions, and these chains may be so connected that under pressure they will collapse to allow free passage 70 through the enclosure. Secured to the outer edges of the doors by any suitable means, are the flexible rubber strips 19, which extend beyond said edges and contact with the inner surfaces of the vertically disposed 75 sides of the enclosure, to form a sealing means to prevent draughts from passing therethrough. Secured to the top and to the bottom by any suitable means, are the 80 weather strips 20. The upper strips contact with the portion 12 of the enclosure 85 while the lower strips contact with the floor 21. The foregoing is descriptive of the general type of door at present in use, and in which the door is revolved as a unit, or it may be pivoted about the disc so that it 90 may be collapsed to allow free passage 95 through the door enclosure.

My improvement lies in the sealing means I employ between the inner edges of the door sections and the centre post. Extending 100 from top to bottom of the post and in alignment with the centre of the inner edges of the door frames, when in their normal or working position, are the flexible weather strips 105 22, which may be of tubular form, as shown, or which may consist of flat thin rubber strips doubled over to form air pockets designated 23. The strips are secured between the clamping bars 24, which are secured to the posts by means of the screws 25. The 110

bars or clamps 24 are so formed that their outer edges overlap the part of the weather strips adjacent the centre post, so that said weather strips are securely held and rotate with the door sections and the centre post when rotated in the direction indicated by the arrow 26.

In operation, the spring construction of the weather strips presses the outer faces against the inner edges of the doors to prevent air from passing therethrough. It will also be seen that by uncoupling the chains, or by breaking their connections, the door sections may be swung towards one another without causing undue wear on the weather stripping, which assumes the shape shown in Figure 3 and designated 27.

It will be readily seen that by sealing a door at the centre in the manner herein detailed, no air can pass between the centre post and the inner edges of the door, a very desirable feature in doors of this class. The

device is very easily attached to this type of revolving door and may be assembled thereon without dismantling or interfering with the general working of the door.

Having thus described my invention, what I claim is;—

In a revolving door structure the combination of a central stationary post about which the wings of the door revolve, clamping plates fastened to said post with the edges of adjacent plates spaced apart to provide vertically extending channels and a plurality of elastic tubes, each having a beaded portion secured in one of said channels, said tubes being adapted to press against the inner edges of said wings to seal the space between the wings and the post during the operation of the door structure.

In witness whereof, I have hereunto set my hand.

HUGH M. KENNEDY.
